2 Sheets-Sheet 1

FIG. 1.

FIG. 2.

The diagram illustrates a circuit board assembly. At the top, a component labeled 34 is positioned above a central rectangular area. To the right of this area, components 35 and 36 are placed side-by-side. Below the central area, components 37 and 38 are located. A horizontal line extends from the right side of the central area, ending at a terminal labeled 91. Another terminal, labeled 12, is located at the bottom right corner of the central area. The entire assembly is mounted on a base plate, with various connection points marked by small circles (e.g., 1, 2, 3, 4, 5, 6, 7, 8, 9, 10, 11) along the perimeter of the central rectangular area.

UNITED STATES PATENT OFFICE.

CHARLES H. ALLAN, OF RYEGATE, MONTANA.

ATTACHMENT FOR TYPOGRAPHICAL MACHINES.

Application filed August 13, 1927. Serial No. 212,661.

In present day practice, the matrices of linotype machines are provided with upper and lower type characters, generally known as "light face" and "black face," respectively. Means are necessarily provided to bring either the upper or lower type character in front of the mold slot at will. According to one method, if it is desired to bring the lower character in front of the mold, the matrices 10 are raised in the assembling elevator above their normal or lower position, and are subsequently carried into the first elevator in this same relative position. According to the second practice, the matrices are set in 15 lower position in the assembling elevator and transferred to the first elevator, the subsequent downward movement of the latter being determined somewhat above its normal limit so that the lower characters are 20 brought in front of the mold slot. According to the first system, there is apt to be some difficulty in delivery to the first elevator, while according to the second system the operator has heretofore been subjected to certain difficulties. Thus he is forced to reach 25 around the first elevator to position a spacer or "flipper" over the lock rod, which is a dangerous practice in itself, and further, when this adjustment has been made, it frequently 30 escapes the operator's attention, and he continues to cast black face when light face is intended. The purpose of my present invention is to overcome the difficulties heretofore encountered in the above described second mode of operation, which with my improvements I believe to be superior to the first.

My invention consists in the provision of an accessory complete in itself, which may be attached to the vise jaw frame of the machine convenient to the reach of the operator, and which when adjusted for black face casting will present a signal which can hardly escape the operator's attention.

An embodiment of my invention is illustrated in the accompanying drawings, wherein:

Figure 1 is a top plan view of my improved device.

Figure 2 is a section on line 2-2 of Figure 1.

Figure 3 is a section on line 3-3 of Figure 1, enlarged.

Figure 4 is a section on line 4-4 of Figure 1, enlarged.

Figure 5 shows my device as attached to a linotype machine of standard design, only

such parts of the latter being shown as to illustrate the application of my invention.

Figure 6 is a section on line 6-6 of Figure 5.

Figure 7 is a top plan view of a modified form of signalling device.

Figure 8 is a side elevation of Fig. 7 with parts broken away.

Figure 9 is a section on the line 9-9 of Fig. 8.

Referring particularly to Figures 1 to 4, 10 represents a guide frame or block having a longitudinal groove 11 wherein is reciprocable a slide 12. Slide 12 is provided with 70 a pin 13 fixed to its upper surface and projecting through a longitudinal slot 14 of a cover plate 15 screw-attached to frame 10 to hold the slide between its guideways. A spring tongue 16 preferably bent in the manner shown in Figure 2, is secured to one end of slide 12 and this tongue carries at its extremity a spacer block 17, the block and tongue having a thickness equal to the distance between the upper and lower type 80 characters of the matrices. Tongue 16 is of sufficient strength to hold block 17 in the position indicated, and its end 18 is preferably turned up as shown. The other end of slide 12 is turned up to form a handle 19.

A plaque 20 is swingable about a vertical pivot 21 secured by means of nut 22 and collar 23 in a counter-bored recess in frame 10 at one side of slide 12. The lower edge of plaque 20 is provided with a longitudinal 90 groove 24 into which pin 13 is adapted to take. A resilient tongue 25, fixed to one end of cover plate 16, bears yieldingly on slide 12 to resist its free movement.

The tongue is slidable relative to the frame 95 from the full-line position of Figures 1 and 2 to the broken-line position, and by reason of the pin and slot connection between the slide and plaque 20, the latter is swung from its full-line position of these figures, to the broken-line position.

The above described self-contained device is preferably attached to the vise jaw frame 26 of the machine, Figure 5, to the right of the first elevator, by a single headed screw 27. 105 This screw engages in a counter-sunk bore in block or frame 10 below slide 12, so that in the construction shown, element 10 will be secured to the vise jaw frame before the device is assembled. The whole is so positioned 110 that handle 19 is convenient to the reach of the operator, and block 17, when in the posi-

tion of Figures 1 and 2, will lie above and free of the usual lock bar 28. As described above, when block 17 is in its extended position relative to frame 10, plaque 20 will take 5 the dotted line position indicated in Figures 1 and 2 and will present a broadside 29 to the view of the operator. This side of the plaque is preferably colored red so as to stand out clearly. In this manner, the operator has a 10 distinct reminder that he is casting black face. When the slide is moved to the right, block 17 will be withdrawn from register with lock bar 28 and screw 30 so that the first elevator can descend to light face position. 15 In this position the plaque or flag 20 presents an edge to the view of the operator so that it is not noticeably visible.

In some types of machines an adjustment rod for the vise jaw extending across the top 20 of the vise jaw frame is provided, and operates in such a manner as to interfere with a signalling device operating as above described. In Figures 7 to 9, I have shown a modified form of signalling device which 25 will be found preferable in many cases.

Referring to Figures 7 to 9, 31 indicates a block to receive a slide, 12 and 32 a cover secured thereto. The cover is provided with an elongated slot 33 and to the rear of this 30 slot the cover has two integral lugs 34 and 35. A plaque 36 is provided at its lower lateral edges with pins journalled in aligned apertures in lugs 34 and 35. The slide element is the same as described in connection with 35 the first embodiment, with the exception that instead of pin 13, it is provided with a cam lug 37 which projects through slot 33.

When the slide is at the extreme right, lug 37 lies to the right of plaque 36 so that the 40 inner face of the latter rests against cover 32 as clearly shown in Figure 7. When the slide is pushed to the left, however, the cam engages the plaque and throws it into the position shown in Figures 8 and 9. A spring clip 45 38 is secured to the rear of the plaque so that when the latter is in its upright position the foot of this clip contacts with the cover plate and tends to throw the plaque forward. Consequently, as soon as the slide is returned to 50 its right limit position, the plaque will be thrown forward into the position of Figure 7. In this construction also the face of the plaque toward the operator is preferably painted in an arresting color.

55 While I have necessarily described a specific embodiment of my invention, it will be understood that I do not intend to be limited except as determined in the following claims.

I claim:

60 1. The combination with a type-casting machine employing two type-character matrices, said machine having an elevator, a lock rod released upon downward movement of said elevator into contact therewith, and a 65 slotted mold, of a block movable into position

over said lock rod to arrest said elevator in its downward movement whereby the lower type character of a matrix carried by said elevator is positioned in front of the mold slot, manually operable means for moving the block, and a signaling device automatically set in view of the operator when said block is so moved. 70

2. The combination with a type-casting machine employing two type-character matrices, said machine having an elevator, and a lock rod released upon downward movement of said elevator into contact therewith, of a block movable into and out of register with said lock rod, manually operable means for moving the block, and a signaling device thrown into and out of signaling position in dependence upon the movements of said block. 75

3. The combination with a type-casting machine employing two type-character matrices, said machine having an elevator, and a lock rod released upon downward movement of said elevator into contact therewith, of a block movable into and out of register with said lock rod, manually operable means for moving the block, and a pivoted signaling device thrown into and out of signaling position in dependence upon the movements of said block. 80

4. The combination with a type-casting machine employing two type-character matrices, said machine having an elevator, and a lock rod released upon downward movement of said elevator into contact therewith, of a slide operatively positioned on a fixed part of the machine to the right of said elevator, a block in connection with said slide at one end thereof, said block being disposable above said rod upon appropriate movement of the slide, an operating handle on the other end of the slide convenient to the reach of the operator, and signaling means automatically set upon movement of said slide. 100

5. The combination with a type-casting machine employing two type-character matrices, said machine having an elevator, and a lock rod released upon downward movement of said elevator into contact therewith, of a horizontal slide operatively positioned on a fixed part of the machine, a block in connection with said slide at one end thereof, and adapted to be positioned above said lock rod upon appropriate movement of said slide, means in connection with the slide manually engageable to move the latter, and a pivoted signaling member automatically swung into signaling position upon such movement of said slide. 115

6. The combination with a type-casting machine employing two type-character matrices, said machine having an elevator, and a lock rod released upon downward movement of said elevator into contact therewith, of a horizontal slide operatively positioned on a 120

fixed part of the machine, a block in connection with said slide at one end thereof and adapted to be positioned above said lock rod upon appropriate movement of said slide, and 5 a pivoted plaque adapted to be swung into broadside position to the view of the operator upon such movement of said slide.

7. The combination with a type-casting machine employing two type-character matrices, 10 said machine having an elevator, and a lock rod released upon downward movement of said elevator into contact therewith, of a horizontal slide operatively positioned on a fixed part of the machine, a block in connection 15 with said slide at one end thereof and adapted to be positioned above said lock rod upon appropriate movement of said slide and a horizontally pivoted plaque adapted to be swung into broadside position to the view of the operator 20 upon such movement of said slide.

8. The combination with a type-casting machine employing two type-character matrices, said machine having an elevator, and a lock rod released upon downward movement of 25 said elevator into contact therewith, of a horizontal slide element operatively positioned on a fixed part of the machine, a block in connection with said slide element at one end thereof and adapted to be positioned 30 above said lock rod upon appropriate movement of said slide element, a plaque horizontally pivoted adjacent said slide and normally lying in a substantially horizontal plane, and means on said slide element to engage said 35 plaque and move it into upright position upon the movement of the slide element.

9. The combination with a type-casting machine employing two type-character matrices, said machine having an elevator, and a lock 40 rod released upon downward movement of said elevator into contact therewith, of a horizontal slide element operatively positioned on a fixed part of the machine, a block in connection with said slide element at one end thereof 45 and adapted to be positioned above said lock rod upon appropriate movement of said slide element, a plaque horizontally pivoted adjacent said slide and normally lying in a substantially horizontal plane, means on said 50 slide element to engage said plaque and move it into upright position upon the movement of the slide element, and means tending to swing said plaque back to horizontal position upon the return of said slide.

10. The combination of a type-casting ma-

chine employing two type-character matrices, said machine having an elevator, and a lock rod released upon downward movement of said elevator into contact therewith, of a horizontal slide element operatively positioned on 60 a fixed part of the machine, a block in connection with said slide element at one end thereof and adapted to be positioned above said lock rod upon appropriate movement of said slide element, a plaque element horizontally pivoted at one side of said slide, and normally lying in a substantially horizontal plane across said slide, and a cam lug on said slide adapted to swing said plaque into substantially upright position upon movement 70 of the slide.

11. The combination of a type-casting machine employing two type-character matrices, said machine having an elevator, and a lock rod released upon downward movement of 75 said elevator into contact therewith, of a horizontal slide element operatively positioned on a fixed part of the machine, a block in connection with said slide element at one end thereof and adapted to be positioned 80 above said lock rod upon appropriate movement of said slide element, a plaque element horizontally pivoted at one side of said slide, and normally lying in a substantially horizontal plane across said slide, a cam lug on 85 said slide adapted to swing said plaque into substantially upright position upon movement of the slide, and spring means tending to swing said plaque back to horizontal position upon the return of said slide. 90

12. The combination with a type-casting machine employing two type-character matrices, said machine having an elevator, and a lock rod released upon downward movement of said elevator into contact therewith, of a 95 guide frame, a slide horizontally reciprocable therein, a block in connection with one end of said slide and reciprocable therewith, a signalling device carried by said frame, means to readily attach said frame to a fixed part of the machine with said block reciprocable into and out of register with said lock bar, and operating means between said slide and signalling device whereby the latter is controlled 100 in dependence upon the movements of the former. 105

In testimony whereof I have hereunto set my hand.

CHARLES H. ALLAN.
